UNITED STATES PATENT OFFICE.

ULRICH REIFFER, OF ST. LOUIS, MISSOURI, ASSIGNOR OF ONE-HALF TO
GOTTLIEB RUPP, OF SAME PLACE.

WASHING-MACHINE.

SPECIFICATION forming part of Letters Patent No. 530,900, dated December 11, 1894.

Application filed November 9, 1893. Serial No. 490,450. (No model.)

To all whom it may concern:

Be it known that I, ULRICH REIFFER, of the city of St. Louis, in the State of Missouri, have invented a certain new and Improved Washing-Machine with Wringer Attached, of which the following is a full, clear, and exact description, reference being had to the accompanying drawings, forming part of this specification.

10 My invention relates to certain improvements in machines for washing and wringing clothes; and my invention consists in features of novelty hereinafter fully described and pointed out in the claims.

15 Figure I is a side elevation of my improved machine, part in section. Fig. II is a top or plan view of the rubbing band or belt, and its supporting rollers. Fig. III is a vertical section, taken on line III—III, Fig. I. Fig.

20 IV is a similar view, taken on line IV—IV, Fig. I. Fig. V is a vertical section, taken on line V—V, Fig. VI. Fig. VI is a section taken on line VI—VI, Fig. V, with the rubbing belt or band removed. Fig. VII is a detail section,

25 illustrating the manner of securing the rollers or rounds of the flexible bottom to the supporting wires. Fig. VIII is a detail, perspective view, showing the manner of securing the cross strips of the flexible or yielding

30 bottom to their supporting wires. Fig. IX is a detail, longitudinal section, showing the manner of securing the cross strips of the rubbing belt or band in place. Fig. X is a detail section, showing one end of one of the

35 rollers of the rubbing band or belt.

Referring to the drawings, 1 represents a suitable frame-work, supported on legs 2.

3 represents the body of the machine, in which the water is placed.

40 4 represents a yielding or flexible bottom, located in the body 3, and consisting of wires 5, to which rollers or rounds 6 are secured, as shown in Fig. VIII. The upper ends of the wires 5 terminate in springs 7, one spring being secured to the frame 1 at 9, and the other

45 spring being secured to a shaft 10, provided with a ratchet 11 engaged by a pawl 12, as shown in Fig. I. By turning the shaft 10 in the proper direction, the flexible bottom may

be lengthened or shortened, as may be desired.

Above the flexible bottom 4 is the rubbing band or belt 13, composed of cross-strips 14 secured to narrow endless strips 15 of canvas or other suitable material. (See Figs. II, V and IX.) The belt or band passes around rollers 16, journaled in, or resting upon strips 17, hinged to the frame 1 by means of a rod 18. (See Fig. VI.) The free ends of the strips 17 are connected by a cross-piece 19, and by taking hold of this cross-piece, the rubbing belt or band may be raised upon the hinge 18, to give access to the lower part of the machine. The journals 20 of the rollers 16, are extended beyond the strips 17, so as to rest in notches 1^a of the frame 1, as shown in Fig. IV, to provide a firm support for the rollers 16, when in their working position.

On one end of the journals 20, are sprocket wheels 21, around which pass an endless chain 22, which also passes around a sprocket wheel 23, on the journal 24 of the lower wringer roller 25; this roller being provided with a crank 26, by which it is turned to operate the wringer, as well as to operate or turn the rubbing belt or band 13. The rollers 16 are provided with sprockets 27, which fit between the rounds 14, and move the belt or band.

29 represents semi-circular strips secured to the under side of the strips 17, and beneath which the belt or band 13 passes, so as to prevent its upward or vertical movement under the pressure of the clothes when the machine is being operated. The belt or band, at top, passes over strips 30, which are also secured to the strips 17. The preferred manner of securing the strips 29 to the strips 17, is by means of a bracket 32, as shown in Figs. III and IV. The preferred manner of securing the journals 20 to the rollers 16 is illustrated in Fig. X.

35 represents uprights secured to the strips 17 and 30, by means of screws 36, or otherwise. These uprights form the support for the journals 24 of the lower roller 25 of the wringer, and their upper ends are slotted to receive the boxes 37 of the upper roller 38 of the wringer. Springs 39 are placed between

the boxes of the upper roller and a cross-piece 40 that connects the uprights 35.

The form or construction of the wringer, *per se*, does not differ materially from that of 5 any ordinary wringer.

41 represents braces connecting the upright strips 35 with the horizontal strips 17.

I claim as my invention—

1. In a washing machine, the combination 10 of the frame supporting the body 3, an adjustable flexible bottom 4 supported in the body, a frame pivoted to said body, rollers journaled in the pivoted frame, a rubbing band or belt mounted upon the rollers which are journaled 15 in the frame, semi-circular strips beneath which the rubbing band or belt passes sprocket-wheels keyed to the journals of the rollers, a sprocket chain passing around said sprocket-

wheels, and a crank for operating one of the sprocket-wheels, substantially as and for the 20 purpose set forth.

2. In a washing machine, the combination of a frame, a body 3 secured to the frame, a bottom 4 located within the body, a rubbing band or belt 13, rollers upon which the rubbing band or belt is mounted, hinged strips 25 17 in which said rollers are journaled, semi-circular strips 29 beneath which the band or belt passes, and strips 30 over which the band or belt passes, substantially as and for the 30 purpose set forth.

ULRICH REIFFER.

In presence of—

A. M. EBERSOLE,
C. G. EDWARDS.
